United States Patent Office

Des. 177,575
Patented May 1, 1956

177,575

CUP

Leonard Louik, Pittsburgh, Pa., assignor to Plastic Sales, a partnership of Pennsylvania

Application September 2, 1954, Serial No. 32,137

Term of patent 7 years

(Cl. D44—9)

Fig. 1. Fig. 2.

Fig. 2 is a view at right angles thereto;

Fig. 3 is a plan view of Fig. 2; and

Fig. 4 is a perspective view thereof.

I claim:

The ornamental design for a cup, as shown.
